UNITED STATES PATENT AND TRADEMARK OFFICE
Certificate

Patent No. D. 646,563 S

Patented: October 11, 2011

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Richard Louis Bontrager, Ripon, CA (US); Randall Glenn Strange, Manteca, CA (US); and Joseph Torquato, Hollister, CA (US).

Signed and Sealed this Eighth Day of April 2014.
